UNITED STATES PATENT OFFICE.

MICHAEL T. CLANCY, OF CLIFTON HEIGHTS, PENNSYLVANIA.

COMBINED BOOK CLASP AND HANDLE.

SPECIFICATION forming part of Letters Patent No. 510,161, dated December 5, 1893.

Application filed September 6, 1893. Serial No. 484,925. (No model.)

To all whom it may concern:

Be it known that I, MICHAEL T. CLANCY, a citizen of the United States, residing at Clifton Heights, in the county of Delaware and State 5 of Pennsylvania, have invented certain new and useful Improvements in a Combined Book Clasp and Handle, of which the following is a full, clear, and exact description, reference being had to the accompanying drawings, forming a part of this specification.

The nature of this invention is a combined clasp and handle for books, the same being applicable, more especially, to the sample and account books carried by canvassers and so- 15 licitors.

The invention consists in the combination with a book, of a handle hingedly connected with the edge of one of the covers, and a clasp or yoke similarly connected with the opposite 20 edge of the other cover, and adapted to embrace the handle member and engage suitable catches on that cover to which the handle is attached, as hereinafter particularly described.

25 In the annexed drawings,—Figure 1 is a perspective view of a portion of a book to which the device is applied, the book being represented as clasped. Fig. 2 is a similar view showing the book unclasped, prepara- 30 tory to its being opened.

A represents a book and B my improved device applied thereto. This device comprises two members, namely, a clasp b and handle c. The clasp is preferably constructed 35 of a piece of stout wire bent into the form of a yoke, its free ends being hingedly connected with the front edge of one of the covers of the book. In the present instance the extremities of the clasp are looped and connected 40 with suitably-disposed eyes, d, on the edge of the cover. On the edge of the other cover

there are fixed two eyes, e, which constitute catches with which the yoke may be engaged. Attached to these eyes are the looped ends of a handle-yoke, c, preferably of wire, which may or may not, as desired, be provided with a hand-hold, c'. The width of the yoke, c, is less than that of the clasp-yoke, to the end that the former will freely extend through the latter, and thus not interfere with the ma- 45 nipulation of the yoke b, during the clasping or the unclasping of the book, as represented in the drawings.

By the above described construction, it will be seen that when the book is clasped there 50 is afforded a simple and efficient handle by which it may be conveniently carried, and this without any liability of the book becoming accidentally unclasped, the handle as will be observed serving as a guard for the clasp. 55

I claim as my invention—

1. A combined clasp and handle for books, comprising a clasp-yoke hingedly connected with one cover of the book, catches on the opposite cover with which said yoke is adapt- 60 ed to engage, and an inner handle-yoke hingedly connected with said latter cover, substantially as described.

2. A combined clasp and handle for books, comprising a clasp-yoke, hinge eyes on one 65 edge of the cover, catch eyes on the edge of the opposite cover, and a handle-yoke hingedly connected with said catch eyes, substantially as described.

In testimony whereof I have hereunto af- 70 fixed my signature in the presence of two sub- 75 scribing witnesses.

MICHAEL T. CLANCY.
